UNITED STATES PATENT OFFICE.

JEAN M. LOBIT, OF NEW YORK, N. Y.

ASSEMBLING MACHINE.

Application filed August 18, 1922. Serial No. 582,593.

This invention relates to machines for producing cast lines or bars of words as a substitute for type setting. More specifically, the invention relates to the assembling mechanism of such machines and has for one of its principal objects to simplify such assembling mechanism and to increase its reliability. Other objects and advantages will appear as the invention is hereinafter disclosed.

Referring to the drawings which illustrate what I now consider a preferred form of machine,

Fig. 1 is a side elevation, partly in section, of the assembling mechanism.

Fig. 2 is a front elevation, partly in section, of the assembling mechanism.

Fig. 3 is a front elevation of one of the special magazines.

Fig. 4 is a fragmentary detail rear elevation of one of the magazines and a part of the release mechanism.

Fig. 5 is a detail sectional view taken substantially on the line 5—5 of Fig. 4.

Fig. 6 is a fragmentary detail front elevation of the special magazine shown in Fig. 3.

Fig. 7 is a section taken substantially on the line 7—7 of Fig. 6.

Machines, variously known as linotype, intertype, etc., are now in common use. These machines comprise assembling mechanism and slug-casting mechanism. The assembling mechanism comprises a receiver adapted to support a magazine or magazines removably mounted thereon or therein, each of such magazines being adapted to hold desired matrices each adapted to cast a letter, numeral or other character. The assembling mechanism comprises also a key-board and connections whereby, when any key is operated, a matrix bearing a character impression corresponding to that key is released from a magazine and delivered to the passage or conduit leading to the casting mechanism. When enough matrices are arranged to form a line or bar they are carried to the casting mechanism where a line or bar is cast into a slug by the last mentioned mechanism.

Assembling mechanisms as now constructed are comparatively complicated and require a great deal of attention and supervision to maintain uninterrupted service. In fact, even with careful supervision these machines now in use are subject to time-

consuming shut-downs for repairs and adjustments. Furthermore, in order to provide for the wide range of characters necessary in accomplishing the work, the key-board embodies a large number of keys, including those for characters infrequently employed, and the key-board-controlled connections are excessive in number.

In accordance with my invention I greatly simplify the key-board and connected parts and provide special magazines for supplying special matrices, the release of the matrices of these special magazines being selectively controlled preferably by keys carried by such magazines.

Referring to Figs. 1, 2, 4 and 5, it will be seen that the assembling machine comprises a frame 10 adapted to receive a plurality of magazines 11, 11, etc. Each of the magazines 11 is provided with brackets 12 having lugs 13 which are slidably engageable in channels or grooves 14 provided in the frame 10. By virtue of this structure, various magazines 11 may be inserted into the open front of the frame 10 from the front or back of the machine, and moved rearwardly or forwardly to operative position. To facilitate such manipulation of the magazines they may each be provided with handles 15.

The magazines 11 being similar, a description of one will suffice for all. Calling attention to Figs. 2 and 5, it will be seen that the magazine 11 there illustrated is provided with a plurality of spaced partitions 16 forming a plurality of matrix-receiving passages or chutes 17. Each of these chutes 17 is open at top and bottom whereby a plurality of matrices 18 may be inserted from the top and discharged at the bottom. Means are provided for releasably holding the matrices 18 in each chute 17 and for selectively controlling the discharge of the matrices one at a time and at will when the corresponding magazine 11 is in position over the delivery channels 19. Such means are preferably constructed as follows:

Each chute 17 is provided at its rear with an escapement pawl 20, each of said pawls being pivotally mounted at 21 on the rear of the magazine 11. Each pawl 20 is provided with a tension spring 22, secured at one end to a corresponding one of brackets 23, carried by the magazine 11, and at its other end to the upper end of the pawl. These springs 22 serve to bias the corre-

sponding pawls to the matrix-holding position shown in Fig. 5. Each of the pawls 20 is provided with a pair of dogs or lugs 24, 25, which are adapted to extend through 5 openings in the rear wall of the magazine 11 alternately to extend into the path of the shoulders 26 of the matrices. Referring specifically to Fig. 5, it will be seen that when the pawl 20 is in the normal position, 10 there shown, chute 17 may be charged with matrices 18 and they will be held in the chute by engagement of the dog 25 with the shoulder 26 on the lowermost matrix. If the pawl 20 is turned counter-clockwise, the 15 dog 25 will be withdrawn permitting the lowermost matrix to drop from the magazine. Such movement of the pawl, i. e., to withdraw the dog 25, causes the dog 24 to move into the path of and engage the 20 shoulder 26 of the next to lowermost matrix to prevent the latter from dropping from the magazine 11. When the pawl 20 is permitted to return to normal position (Fig. 5) under the action of its spring 22, the dog 24 25 is withdrawn and the matrices drop until the shoulder 26 of the then lowermost matrix engages the dog 25. The pawls 20 are selectively controlled and operated by a key-board and connections which I shall now 30 proceed to describe.

A key-board is provided, as shown in Figs. 1 and 2. This key-board comprises a plurality of keys 30 each provided on a corresponding one of key levers 31 fulcrumed 35 or pivoted at 32 to the machine. Each key lever 31 is pivotally connected at its rear end to a corresponding one of bars 33 each slidably mounted for vertical sliding movement in reverse directions, in the bracket 34 carried by and at the rear of the machine. The upper end of each bar 33 is inclined and adapted to engage and operate a corresponding one of pawls 20 of any magazine 11 positioned over the delivery channels 19.

The magazines 11 are so loaded and the 40 design is such that when any key 30 is depressed the lowermost matrix in a corresponding chute 17, i. e., a matrix corresponding to the particular key depressed, will be released from that magazine 11 then in operative position, and will drop into and through the corresponding delivery channel 19. Upon release of the actuated key the parts are automatically restored by gravity 45 to the position shown in Figs. 1 and 5 except that one matrix will have been discharged.

From any chute 17, a matrix 18 passing therethrough will be discharged upon the 50 conveyer belt 36 which continuously moves in the direction of the arrow (Fig. 2) by virtue of propelling mechanism (not shown). From the belt 36 the matrices are discharged into the passage or conduit 37 which leads 55 to the usual slug-casting mechanism. It will

be understood that when enough matrices 18 are arranged in the passage 37 to form a line or bar, they are carried to the left through the usual instrumentalities (not shown) and a line, bar, or slug is cast automatically by the usual slug-casting mechanism (not shown).

The key-board above described, and which I shall term the main key-board, is provided with such number of keys and each magazine 11 is provided with such number of chutes 17 as are necessary to accommodate the characters commonly employed in printing. For special characters I prefer to provide the 70 following mechanism.

A special magazine, or special magazines, 111 are provided. (See Figs. 3, 6 and 7.) So far as the elements 112, 113, 115, 116 and 117 are concerned, these are substantially identical to the elements 12, 13, 15, 16 and 17, respectively, of the magazines 11. Each special magazine 111 is adapted to receive matrices 118 which are the same as the matrices 18 except as to the differences in characters. While the control of the 80 matrices 118 might be effected from the main key-board, I prefer to provide each special magazine 111 with its own auxiliary key-board and control mechanism. Calling 85 attention to Figs. 3, 6 and 7, this mechanism may be constructed substantially as follows.

A plurality of keys 130 are provided, one for each chute 117 of the magazine 111. Each of these keys 130 is secured to and carried by a corresponding one of escapement pawls 120. The latter are each pivoted or fulcrumed at 132 to the front of the magazine 111. As in the case of the magazines 11 each escapement pawl is provided with dogs or lugs 124 and 125 adapted to operate, with respect to the matrices 118, in substantially the same manner as in the case of the mechanism above described in connection with the magazines 11 and the main key-board. It will be noted, however, that each key 130 is mounted directly on its corresponding escapement pawl 120 and the dogs 124, 125 cooperate with the shoulders 126, of the matrices 118, which are toward the front of the magazine 111. Furthermore, instead of employing tension springs to bias the pawls 120 to the position illustrated in Fig. 7, I employ compression springs 122 each mounted between a corresponding pawl 120 and bracket 123.

The keys 30 of the main key-board and the keys 130 of each auxiliary key-board may be provided with the usual indicia, each corresponding to the matrix which is released by the particular key.

The operation of the assembling machine may now be summarized as follows. One or more magazines 11 are placed in the frame 10. One of these magazines is placed 125 in position over the delivery channels 19. 130

The operator now manipulates the main key-board in the usual manner successively to discharge the desired matrices from the magazine 11, through the delivery channels 19, to the belt or conveyer 36 and thence to the channel or conduit 37 whence, when enough matrices have been arranged to form a bar or line, they are carried to the left and a line, bar or slug is automatically cast by the casting machine (not shown). The operator then arranges another line or bar and so on. When a magazine 11 is no longer desired it is simply pushed toward the front or rear of the machine, and another desired magazine 11 substituted therefor. Whenever it is desired to employ a special character or special characters, the magazines 11, at that time in the frame 10, are pushed to the rear and any desired special magazine 111 is moved into the frame 10 from the front thereof to the operative position over the delivery channels 19. The key or keys 130 of the auxiliary key-board of the particular special magazine 111 are then operated to release a desired one or more of the special matrices 118. The special magazine 111 may then be removed from the front of the machine and the magazine 11 restored to position over the delivery channels 19.

In accordance with the provisions of the patent statutes, I have herein described the principles of operation of my invention, together with the apparatus which I now consider to represent the best embodiments thereof but I desire to have it understood that the apparatus shown is only illustrative and that the invention can be carried out by other means. Also, while it is designed to use the various features and elements in the combinations and relations described, some of these may be altered and others omitted without interfering with the more general results and effects outlined, and the invention extends to such use.

What I claim is—

1. An assembling mechanism for slug-casting machines comprising in combination, a magazine-receiver, a plurality of magazines each adapted to be mounted in said receiver, each of said magazines having matrix-receiving chutes, a main key-board and connections therefor for selectively releasing matrices from any of said magazines when mounted in a predetermined position with respect to said assembling mechanism, a special magazine adapted to be charged with matrices and adapted to be mounted in said receiver, an auxiliary key-board carried by said special magazine, and means operable by said auxiliary key-board for selectively releasing matrices from said special magazine.

2. An assembling mechanism for slug-casting machines comprising in combination,

a magazine-receiver, a plurality of matrix-magazines each adapted to be mounted in said receiver, a main key-board and connections therefor for selectively releasing matrices from any of said magazines when mounted in a predetermined position in said assembling mechanism, a special matrix-magazine adapted to be mounted in said receiver, an auxiliary key-board carried by said special matrix-magazine, and means operable by said auxiliary key-board for selectively releasing matrices from said special matrix-magazine.

3. An assembling machine for slug-casting machines comprising in combination, a magazine-receiver, a plurality of interchangeable matrix-magazines, a main key-board and connections therefor for selectively releasing matrices from any of said matrix-magazines when in a predetermined operative position in said assembling machine, a special matrix-magazine adapted to be mounted in the same predetermined operative position adapted to be occupied by each of said first mentioned matrix-magazines, an auxiliary key-board, and means operable by said auxiliary key-board for selectively releasing matrices from said special matrix-magazine.

4. In combination, a special matrix-magazine adapted to be mounted in an assembling machine in the position normally occupied by a main matrix-magazine, said special matrix-magazine including a key-board carried thereby, and means carried by said special matrix-magazine and controlled by said key-board for selectively releasing matrices from said special matrix-magazine.

5. The combination set forth in claim 1 in which a plurality of interchangeable special magazines are provided.

6. An assembling mechanism for slug-casting machines comprising in combination, a common magazine-receiver, a series of delivery channels, a plurality of interchangeable matrix-magazines each adapted to be positioned in said receiver in cooperative relation with said channels, a keyboard and connections therefor adapted to selectively release matrices into said channels from the one of said magazines positioned in cooperative relation with said keyboard and connections, a special matrix-magazine adapted to be mounted in said common receiver in adjacent relation to said other matrix-magazines and be positioned in cooperative relation with said channels, an auxiliary key-board carried by said special matrix-magazine, and means operable by said auxiliary keyboard for selectively releasing matrices from said special matrix-magazine into said delivery channels when said special matrix magazine is in cooperative relation therewith.

7. An assembling mechanism for slug-

4
casting machines comprising in combination, a magazine-receiver, a plurality of magazines each adapted to be mounted in said receiver, each of said magazines having 5 matrix-receiving chutes, a main key-board and connections therefor including matrix-engaging pawls for selectively releasing matrices from any of said magazines when mounted in a predetermined position with 10 respect to said assembling mechanism, a plurality of interchangeable special magazines

each adapted to be charged with matrices and adapted to be mounted in said receiver, an auxiliary key-board carried by each of said special magazines, and means operable 15 by an auxiliary key-board for selectively releasing matrices from its associated special magazine.

In testimony whereof I hereto affix my signature.

JEAN M. LOBIT.
